UNITED STATES PATENT OFFICE.

CHARLES H. SHEFTALL, OF NEW YORK, N. Y., ASSIGNOR OF ONE-HALF TO
MAX HILBORN, OF NEW YORK, N. Y.

SAD-IRON.

SPECIFICATION forming part of Letters Patent No. 700,444, dated May 20, 1902.

Application filed July 19, 1901. Serial No. 68,877. (No model.)

To all whom it may concern:

Be it known that I, CHARLES H. SHEFTALL, a citizen of the United States, and a resident of New York, county of New York, and State of New York, have invented certain new and useful Improvements in Sad-Irons, of which the following is a specification, reference being had to the accompanying drawings, forming a part thereof, in which similar characters of reference indicate corresponding parts.

This invention relates to sad-irons of that class which are heated by a blast of mixed air and gas interiorly applied, and it is designed as an improvement on the structure covered by my Letters Patent No. 666,115, dated January 15, 1901.

The object of the invention is to provide a device of this character which comprises novel features of utility, durability, and general effectiveness, embodying means for evenly heating the iron throughout the entire area of its smoothing-surface.

In the accompanying drawings, forming part of this specification, Figure 1 is a longitudinal sectional elevation of my improved iron. Fig. 2 is a cross-sectional elevation taken on a line $x-x$ of Fig. 1. Fig. 3 is an inverted plan view of a deflector forming part of the invention, and Fig. 4 is a sectional view of the burner having its parts disconnected.

The body A of the iron is supplied with a recess A', open at the top and back. Formed interiorly around the top edge of the side walls of the body A is a channel a , adapted to engage the lid or top B of the iron.

The open or rear end of the iron is closed by means of a swinging door C, pivotally secured between the side walls of the iron-body.

At the rear end of the iron, formed in the upper surface of the bottom thereof, is a groove a' for-receiving a burner, which will be hereinafter described. At the inner end of this said groove a convex surface or shoulder a^2 is formed, which contacts with the flame from the burner.

For supplying the heating agent to the iron I employ a burner E, which embodies the centrally-located vertical duct e and the horizontal duct e' , the burner depending from and

forming an integral part of the removable top or cover B, whereby it can be readily removed, with the cover, for the purpose of cleaning. The outlet or discharge end of the duct e is enlarged in diameter, whereby an annular shoulder 2 is formed for contact with a wire-gauze disk 4, which is held within the annular groove 3.

The top or cover B of the iron embodies the plates b and b' and the integrally-formed pillars b^3 , b^8 , b^3 , and b^4 , whereby a strong structure is provided, which has an ample air-space 1 to prevent overheating the handle B', which also preferably forms an integral part of the cover B. The pillars b^2 , b^3 , b^3 are each pierced with openings for engaging fastening-screws F, which are threaded into lugs A ^{2} , formed integrally with the body A within the recess A'.

The vertical or inlet duct e of the burner E leads into a vertically-extended channel e^2 , formed in the pillar b^4 , and this said channel communicates with an angularly-extended tube e^3 , which forms an integral part of the cover B. This tube e^3 acts as an inlet for the heating agent, and it is connected to the screw-threaded end g of the tubular supply-nozzle G, which is connected to a flexible hose, as described by my Letters Patent No. 666,115, before mentioned.

Located in front of the burner E is a concaved segmental hood or deflector L. This deflector is semicircular in end elevation, embodying an arch covering the end of the burner E and having the recesses l for lateral discharge of flame, the base of the arch resting upon the floor of the recess A' at its outer end, but the sides cut away to form openings l' for escape of flame around the deflector to afford an even distribution of heat. As a further means for distributing the flame, a rib l^2 is extended downwardly and centrally from the deflector L. The inner end of the deflector L is supplied with an extended base portion L', which rests on the floor of the recess A' and engages the fastening-screw M, which is threaded into the base of the iron-body A.

The disks 4, forming part of the burner E, are formed of malleable wire-gauze, and they are normally of a concaved contour, having a

diameter equal to the enlarged discharge part of the outlet of the duct e' . To attach the disk to the burner, said disk is placed against the shoulder 2, with the concavity inward.

5 Then a cylindrical tool embodying a metallic rod of a diameter equal to the outlet of the duct e' is forced against the convex surface of the disk, whereby said disk is flattened, increased in diameter, and forced within the 10 annular groove 3, where it is effectually and securely retained. Any suitable number of disks may be employed, depending upon the width of the groove 3; but for purposes of illustration I have shown but one.

15 Located within the channel a , between the body of the iron and the lower edge of the lid B, is a strip of asbestos P, which makes a flame-tight joint to retain the heat. This packing is placed within the channel a in a 20 wet or moistened state, and it is then tightly compressed by means of the screws F to maintain a perfectly-tight joint.

In the operation and use of the invention a flexible supply-pipe of any adapted construction and [composition is attached to the 25 nozzle G and led to any suitable mixing and air-compressing apparatus adapted to supply a blast of gas and air to the iron. The burner is then lighted and the door closed, 30 whereby the device is ready for use, and the novel relative arrangement of the burner and deflector and the relative arrangement of the discharge end of the burner and the grooved bottom of the iron causes a continuous and 35 even distribution of the projected flame.

Having thus described my invention, what I claim as new, and desire to secure by Letters Patent, is—

1. As a blast-iron, the combination, of the 40 recessed body having a groove in its bottom, the interior channel around the upper edge of its walls and which is open at the top and rear end, the removable cover embodying the upper and lower plates having the air-space 45 and the integrally-formed pillars between them, the integral burner embodying the inlet-channel, the vertical duct and the horizontal discharge-opening having the annular shoulder and the annular groove for engaging a screen,

and the asbestos packing between the body 50 and cover; with the arched deflector having the central rib, the bottom openings and the front recesses, substantially as shown and described.

2. As a blast-iron, the combination, with 55 the recessed body having a groove in its bottom, an interior channel around the upper edge of its walls and which is open at the top and rear end, the removable cover embodying the upper and lower plates having the 60 air-space and the integrally-formed pillars between them, the integral burner embodying the inlet-channel, the vertical duct and the horizontal discharge-opening having the annular shoulder and contiguous annular 65 groove, and a malleable and normally concaved woven-wire disk within the said groove, and lying flat against the said shoulder; of an arched deflector having openings for discharge of flame on its bottom edges and recesses also for discharge of flame on its front edge and having a central rib for splitting the flame, substantially as shown and described.

3. As a blast-iron, the combination, of the 70 recessed body having the interior channel around the upper edge of its walls and which is open at the top and rear end, and means for closing the rear opening, and the removable cover embodying the upper and lower 75 plates having the air-space and the integrally-formed pillars between them, the integral burner embodying the inlet-channel, the vertical duct and the horizontal discharge-opening having the annular shoulder and the contiguous annular groove for engaging a screen, 80 with the arched deflector having the central rib, the bottom openings and the front recesses, substantially as shown and described.

In testimony that I claim the foregoing as 85 my invention I have signed my name, in presence of two witnesses, this 18th day of July, 1901.

CHARLES H. SHEFTALL.
